UNITED STATES PATENT OFFICE.

JOHN W. AHLGRIM, OF SANTA MONICA, CALIFORNIA.

GAME.

Application filed May 23, 1927. Serial No. 193,522.

This invention relates to games.

An object of the invention is to provide a game apparatus of simple construction and which enables the entertainment of a considerable number of players and observers at one time.

Another object is to provide a game including coordinate, actuatable signal flags and a deck of player's cards; the flags each bearing a different number and being characterized in series of different colors indiscriminately mixed in a field and the cards each divided into diametrical zones which are severally colored to correspond with the colors of the flags and each zone having sections which are numbered to correspond with the correlative flag.

A further object is to provide means for shifting the flags from a concealed to an exposed position visible to players holding the cards and to observers.

Additional objects, advantages and features will be made manifest in the following specification of the herewith illustrated embodiment; it being understood that modifications, variations and adaptations may be resorted to within the spirit, scope and principle of the invention as it is more directly claimed hereinafter.

Figure 1 is a front elevation of the flag box, partly broken away.

Figure 2 is a vertical cross-section of the flag box as mounted to travel from player to player.

Figure 3 is a detail of a part of a resetting bar.

Figure 4 is a perspective of a detached flag stem.

Figure 5 is a perspective of a flag.

Figure 6 is a perspective of a flag mount.

Figure 7 is a diagrammatic plan of the flag box carrier.

Figure 8 is a face view of a player's card.

The game includes a deck of, say forty-eight, cards C here shown as of circular form and having five diametrical zones Z of as many different colors, as red, blue, green, brown and yellow. Each zone is divided into four sections which are variously numbered; sections of the same color on the cards being numbered from "1" to "16". The zones are labelled severally as "Wheat", "Corn", "Oats", "Barley", "Flax"; all similar color zones having the same grain legend. Since there are five colors and grains shown and as each grain zone has four sections and

these of a color run from "1" to "16" the product of the numbered sections and the colors is eighty sections all different either by number or color combination.

The object is for a player to win a point or points by filling out on his cards a full grain zone of four differently numbered sections.

This is accomplished by apparatus having a field of flags F of which a series of eighty is provided as complementary to the five grains of sixteen numbers each.

The full series of eighty flags is mounted on respective stems 2 which may have mounts 3 in which the flags can be readily interchanged from time to time for jumbling their order. The stems stand side to side in a vertical box chamber 4 having front and rear panes 5 of glass under a frame header 7.

It is preferred that duplicate flags at immediately opposite position on the stems be employed so that a similar signal will appear at the front and rear windows. Spaced above the top of the row of stems 2 is a cross-rod 10 which serves for a keeper for light springs 11 attached to the tops of the stems. When a stem is pushed up its spring latches over the keeper rod and this sustains the elevated stem.

The elevated stems may be depressed at will by a universal bar 12, hung by springs 13, above the top of the row of stems. The bar has a push button 14 above the box header 7.

The stems are arranged in groups of five side to side and the flags of each group are spaced vertically in a column (sixteen columns in the chamber 4). The stems are connected to respective off-set levers 15 in any suitable manner here shown as by links 16. The group levers have vertically and laterally offset keys 17 so as to provide ample finger clearance. In their lower positions the levers and the stems are stopped by stepped shoulders 18, Fig. 1, in groups along the bottom of the row.

The levers 15 are loosely mounted on respective pivot axles 20 and are enclosed, except at the keys, by a suitable box 21.

The vertically spaced flags F are concealed in their lower positions by opaque portions O of the front and rear windows 5 and, hence, are unknown to the players who, in turn, have the option of punching down any unpressed key 17 in the bank with the object of lifting into view, over the opaque

area, a flag having a number and color corresponding to a card grain section and number which he holds. The lifted stem 2 moves its flag into display (front and rear) 5 and any player holding the relative grain card, by section number and color, places a marker on the section.

Any player filling a zone with markers must call out "Corner on pit" on such grain 10 as he has cornered. For this he earns a point or score.

The resetting bar 12 is then depressed to restore all flags to concealed position and the play starts over.

15 Preferably the flag box is mechanically carried in an orbit from player to player at a table or counter T within which may stand a game keeper who watches the plays, keeps score and resets the flags from time to time.

20 The box is here shown as attached to a sprocket belt 25 driven by wheels 26. Stools 27 may be placed adjacent to the table or counter for comfort of participants.

All cards will be turned into the game 25 keeper after each play and he will shuffle and reissue them to the players.

The game is designed to cultivate the memory by causing the player to endeavor 30 to memorize the positions of the eighty flags by number so that he can by this capacity quickly select the right keys in his turn.

What is claimed is:

1. In a game a deck of cards each card characterized by diametrical zones of different colors, the zones having numbered sections, no zones of a color having duplicate numbers, and a system of flags each of a color and number corresponding to one of the numbered color sections of the cards, 35 means in which the flags are all arranged in a field and concealed, and means for selectively moving the flags into a visible position.

2. In a game a device including a box having a bank of keys, levers actuated by the 40 keys, a field of colored and numbered flags each operative by a given lever, and a deck

of cards, each having colored and numbered sections corelative to the field of flags.

3. In a game a device including a box having a bank of keys, levers actuated by the 50 keys, a field of colored and numbered flags each operative by a given lever, and a deck of cards, each having colored numbered sections corelative to the field of flags, and means for retaining the flags in a displayed position following key action.

4. In a game a device including a box having a bank of keys, levers actuated by the 55 keys, a field of colored and numbered flags each operative by a given lever, and a deck of cards, each having colored and numbered sections corelative to the field of flags, and for retaining the flags in a displayed position following key action; the respective 60 keys being held in played position by their levers.

5. In a game a device including a box having a bank of keys, a field of colored and numbered flags each operative by a given 70 lever, and a deck of cards, each having colored and numbered sections corelative to the field of flags, and means for retaining the flags in a displayed position following key action, and means for restoring all exposed 75 flags to a concealed position.

6. A game including a field of flags each 80 differently characterized, a deck of player's cards having sections corresponding to the said flags in designation, means for individually moving the flags, means to conceal the flags in one position and expose them in another, means to retain the flags in exposed position, and means for restoring all exposed flags.

7. In a game, a field of movable flags, a case in which the field is mounted and for 85 concealing the flags in one position and exposing them in another therein, a stationary player's table structure, and a means for orbitally moving the case from player to player at the table structure.

JOHN W. AHLGRIM.
